(57) **CLAIM**

We claim the ornamental design for a dust seal cap of front fork for two-wheeled vehicle, as shown and described.

DESCRIPTION

FIG. 1 is a front view;

FIG. 2 is a plan view;

FIG. 3 is a bottom view;

FIG. 4 is a perspective view;

FIG. 5 is a sectional view taken along line 5—5 in FIG. 2; and,

FIG. 6 is a perspective view showing the design on a reduced scale and in position of use on a front fork, which is shown in broken lines for illustrative purposes only and forms no part of the claimed design.
